FIRE DETECTION SYSTEM

Thomas A. Rausch, White Bear Lake, Minn., assignor to
Elan Industries, Inc., St. Paul, Minn.

Filed Mar. 3, 1971, Ser. No. 120,794

Term of patent 14 years

Int. Cl. D29—01; D26—05
U.S. Cl. D72—1 R

Fig. 1

Fig. 2

FIG. 1 is a front perspective view showing the fire detection system of my new design.

FIG. 2 is a left side view.

The back, sides and bottom of the box-like enclosure are flat and unadorned.

I claim:

The ornamental design for a fire detection system, as shown and described.
